(57) **CLAIM**

The ornamental design for children's ride-on vehicle, substantially as shown and described.

DESCRIPTION

FIG. 1 is a perspective view of children's ride-on vehicle, showing my new design;

FIG. 2 is a left side elevational view thereof;

FIG. 3 is a right side elevational view thereof;

FIG. 4 is a front elevational view thereof;

FIG. 5 is a rear view thereof;

FIG. 6 is a top view thereof; and,

FIG. 7 is a bottom view thereof.

The broken lines shown in FIGS. 1-7 are for illustrative purposes only and form no part of the claimed design.
